[57] **ABSTRACT**

In a lighting device for a discharge lamp including a ballast inserted between an AC power source and a discharge lamp the ratio Z_c/Z_L of the capacitive impedance Z_c to the inductive impedance Z_L of the ballast is in the range of 1.9-2.8; the ratio V_L/V_s of the nominal lamp voltage V_L of a discharge lamp to the unloaded voltage V_s of a power source is in the range of 0.7-1.1; and when V_L/V_s is in the range of 1.0-1.1, the ratio V_L/V_s is so determined as to satisfy the equation:

$$Z_c Z_L \geq 9V_L/V_s - 7.1$$

LIGHTING DEVICE FOR A DISCHARGE LAMP**BACKGROUND OF THE INVENTION**

The present invention relates to a lighting device for a discharge lamp and particularly to a lighting device in which a ballast has the optimum requirement for being light in weight and compact.

Generally, a lighting device for a discharge lamp must have the functions of easily starting a discharge lamp, stably maintaining the lighting of the discharge lamp and holding down the output variation of the discharge lamp even if a power source voltage is varied. For this reason a ballast is so constructed that in order to light a discharge lamp the ratio V_L/V_s of the unloaded voltage V_s of a power source to the nominal lamp voltage V_L is a relatively small value of 0.45-0.5.

However, the smaller the ratio V_L/V_s , the larger the ballast with the attendant increase in weight. As set out above, in an attempt to improve the variation rate of a lamp voltage a phase advance type lighting device is used. In this case, if a suitable balance between the inductance L and the capacitance C of the ballast is not taken, a flicker occurs and parts of ballast are increased in size and it is disadvantageous from the practical point of view.

Accordingly, the object of the present invention is to provide a lighting device for a discharge lamp including a ballast capable of being maintained at optimum condition without involving any flickering or fading out and having the optimum requirement of being lit in weight and compact.

SUMMARY OF THE INVENTION

The lighting device according to the present invention including a discharge lamp is operated by an AC power source and a ballast is inserted between the AC power source and the discharge lamp. The ratio Z_c/Z_L of the capacitive impedance Z_c to the inductive impedance Z_L of the ballast is in the range of 1.9-2.8; the ratio V_L/V_s of the nominal lamp voltage V_L of the discharge lamp and the unloaded voltage V_s of the power source is in the range of 0.7-1.1; and when the ratio is in the range of 1.0-1.1, Z_c , Z_L , V_L and V_s are defined to satisfy the following equation:

$$Z_c/Z_L \geq 9V_L/V_s - 7.1$$

When the above-mentioned relation exists between Z_c and Z_L of the ballast and unloaded AC power source voltage V_s and nominal lamp voltage V_L , not only a very stable lighting state of the discharge lamp is maintained, but also a compact, light weight ballast results.

BRIEF DESCRIPTION OF THE DRAWING

FIG. 1 is a schematic diagram showing one embodiment according to the present invention;

FIG. 2 is a schematic diagram showing another embodiment according to the present invention;

FIG. 3 is an explanatory diagram of the characteristics of the device according to the present invention; and

FIG. 4 shows the waveform of a voltage applied to the discharge lamp of FIGS. 1 and 2.

DESCRIPTION OF THE PREFERRED EMBODIMENTS

Referring to FIG. 1 a discharge lamp 2 is connected, through a ballast 3, between the terminals of an AC

voltage source 1. The ballast consists of an inductive impedance element, for example, a choke coil 4 and a capacitive impedance element, for example, a condenser 15. The inductive impedance and capacitive impedance are denoted as Z_L and Z_c , respectively, and the unloaded voltage of the power source 1 and the nominal lamp voltage of the discharge lamp are denoted as V_s and V_L , respectively. Between the terminals of the power source 1 there is connected a pulse generating circuit 6 driven by the voltage of the power source. An output pulse from the pulse generating circuit is fed to a tap 7 of the choke coil 4.

When the switch (not shown) of the power source is thrown in, an output pulse from the pulse generating circuit 6 is applied to the tap 7. The voltage of the output pulse is boosted by the choke coil 4 and a high-tension pulse is generated across the choke coil. The high-tension pulse is applied, in a manner to be overlapped by an AC voltage from the power source, between the electrodes of a discharge lamp 2 to light the discharge lamp. In this circuit arrangement, experiments were conducted by varying not only the ratio Z_c/Z_L of the capacitive impedance Z_c to the inductive impedance Z_L of the ballast, but also the ratio V_L/V_s of the nominal lamp voltage V_L of the discharge lamp to the unloaded voltage V_s of the power source and it was observed that the area in which no flickering and fading out occur is a rectangular area defined by lines a, b, c and d as shown in FIG. 3. From this area an optimal data for permitting the ballast to be smaller in size and light in weight can be obtained.

In FIG. 3 the abscissa and the ordinate are represented as the ratio V_L/V_s (nominal lamp voltage/unloaded voltage of the power source) and the ratio Z_c/Z_L (capacitive impedance/inductive impedance of the ballast), respectively. Let us now explain the reason why the area outside the rectangular area as defined by a, b, c and d is unfit for a lighting device. At the area of $V_L/V_s > 1.1$ fading out occurs irrespective of any value Z_c/Z_L . At the area of $1.0 \leq V_L/V_s \leq 1.1$ the area in which an excellent lighting state is continued is intermingled with the area in which fading out occurs. This is dependent upon the ratio Z_c/Z_L . That is, at the area of $V_L/V_s = 1$ the situation in which $Z_c/Z_L = 1.9$ is different in refiring voltage from the situation in which $Z_c/Z_L = 2.8$. In this case, no fading out occurs with the increase in the value Z_c/Z_L . In FIG. 4A the refiring voltage waveform (peak value V_1) is shown at the area of $V_L/V_s = 1.0$ and $Z_c/Z_L = 2.8$; and in FIG. 4B the refiring voltage waveform (peak value V_2) is indicated at the area of $V_L/V_s = 1.0$ and $Z_c/Z_L = 1.9$. These waveforms are different from each other and the relation $V_2 > V_1$ is obtained. In other words, in the range of 1.0-1.1 of V_L/V_s fading out tends to occur at $V_L/V_s > 1.0$ when $Z_c/Z_L = 1.9$, and fading out occurs at $V_L/V_s > 1.1$ when $Z_c/Z_L = 2.8$. When the ratio Z_c/Z_L is in the range of 1.9-2.8 fading out tends to occur at that point of V_L/V_s in which equation

$$Z_c/Z_L < 9V_L/V_s - 7.1$$

From this it will be understood that a lighting device having a relation of V_L/V_s to Z_c/Z_L corresponding to that right side area as defined by the line a is infeasible from a practical view point.

In that upper area as defined by the line c a value of Z_c/Z_L is greater which means that a capacitive component Z_c is increased. Therefore, a rest period is in-

volved at the lamp current and flickering is caused due to this rest period. In the area of $Z_C/Z_L > 2.8$ flickering takes place irrespective of any value V_L/V_s and it is undesirable from the practical point of view. In an attempt to prevent flickering at a lower temperature ($0^\circ C$) it is some time desirable that Z_C/Z_L be below 2.6.

In those areas as defined by $V_L/V_s < 0.7$ and $Z_C/Z_L < 1.9$, that is, the left side area defined by the line b and the lower side area defined by the line d, the inductive impedance Z_L and capacitive impedance Z_C of the ballast become greater. In this case, a ballast will be large-sized and it is therefore undesirable. To explain in more detail, in those areas the inductive impedance Z_L of the ballast becomes greater than that of a phase lagging type ballast having inductive impedance only and, in addition, a lamp voltage varied with a power source presents no difference from the case in which a phase-lagging type ballast is used.

Let us now numerically explain the discharge lamp lighting device according to the present invention. Use was made of a lighting device for a 110W high output fluorescent lamp having a power source voltage V_s of 200V, a frequency of 50 Hz, a ballast inductance L of 600mH, a ballast capacity C of $7.3\mu F$ and a nominal voltage V_L of 159V. In this case the ratio of the capacitive impedance Z_C to the inductive impedance Z_L is given as follows:

$$\frac{Z_C}{Z_L} = \frac{1}{\omega C} = \frac{1}{2 \times 3.14 \times 50 \times 7.3 \times 10^{-6}} = 2.32$$

The ratio of the nominal voltage V_L to the unloaded voltage of the power source is expressed below.

$$V_L/V_s = 159/200 = 0.795$$

This lighting device falls within the area as specified in FIG. 3, that is, on a point P and exhibits an excellent lighting state.

Then, use was made of a lighting device for a 220W high output fluorescent lamp having a power source voltage of 200V, a frequency of 50Hz, a ballast inductance L of 360mH, a ballast capacitance C of $12.6\mu F$ and a nominal lamp voltage V_L of 173V. In this case the ratio Z_C/Z_L is expressed as follows:

45

50

55

60

$$\frac{Z_C}{Z_L} = \frac{1}{\omega C} = \frac{1}{2 \times 3.14 \times 50 \times 1.26 \times 10^{-6}} = 2.24$$

The ratio V_L/V_s is given below:

$$V_L/V_s = 173/200 = 0.865$$

That is, this lighting device falls on a point Q within the area as defined in FIG. 3 and exhibits an excellent lighting state.

As explained above, a lighting device capable of maintaining an excellent lighting state and having a small-sized, light weight ballast is obtained by restricting the relation of Z_C/Z_L to V_L/V_s specifically to the area as defined by lines a, b, c and d.

The pulse generating circuit 6 as shown in FIG. 1 can be omitted in a case where no pulse is necessary when a discharge lamp is started.

In FIG. 2 there is shown another embodiment according to the present invention in which a leakage transformer 8 is used as an inductive impedance element of a ballast 3. In this case, since the voltage of a power source 1a is boosted by the secondary winding 25 of the leakage transformer, the above-mentioned voltage V_s means a voltage applied between the electrodes of a discharge lamp before the starting of the discharge lamp. In this embodiment the operational function is substantially the same as the embodiment of FIG. 1 and any further explanation is therefore omitted.

What we claim is:

1. A lighting device for a discharge lamp including a discharge lamp fed from an AC power source and a ballast arranged between the discharge lamp and the AC power source and including a capacitive impedance Z_C and an inductive impedance Z_L , in which a ratio Z_C/Z_L of the capacitive impedance Z_C to the inductive impedance is in the range of 1.9-2.8; a ratio V_L/V_s of a nominal lamp voltage V_L of the discharge lamp to an unloaded voltage V_s of the power source is in the range of 0.7-1.1; and when the ratio V_L/V_s is in the range of 1.0-1.1 it satisfies the equation:

$$Z_C/Z_L \geq 9V_L/V_s - 7.1.$$
